UNITED STATES PATENT OFFICE.

**HARRY A. BAUMAN, OF AKRON, OHIO, ASSIGNOR TO THE B. F. GOODRICH COMPANY,
OF NEW YORK, N. Y., A CORPORATION OF NEW YORK.**

DESIGN FOR A HOT-WATER BOTTLE.

Application filed April 13, 1928. Serial No. 26,311. Term of patent 14 years.

To all whom it may concern:

Be it known that I, HARRY A. BAUMAN, a citizen of the United States, residing at Akron, in the county of Summit and State of Ohio, have invented a new, original, and ornamental Design for a Hot-Water Bottle, of which the following is a specification, reference being had to the accompanying drawing, forming a part thereof.

The accompanying drawing shows a side elevation of a hot water bottle embodying my new design, the reverse side of the bottle having the same appearance as that of the side here shown.

I claim:

The ornamental design for a hot-water bottle as shown and described.

HARRY A. BAUMAN.
